UNITED STATES PATENT OFFICE.

DORSEY FROST ASBURY, OF WASHINGTON, DISTRICT OF COLUMBIA.

FUSE.

Application filed September 13, 1920. Serial No. 409,821.

To all whom it may concern:

Be it known that I, DORSEY F. ASBURY, a citizen of the United States, and resident of Washington, in the District of Columbia, 5 have invented certain new and useful Improvements in Fuses, of which the following is a specification.

My invention relates to fuses and particularly to those types employed to effect the 10 ignition of the bursting charges of projectiles.

It is the purpose of my present invention to provide improved means for assuring the safety of the fuse in handling and transportation and the successful and certain 15 operation thereof after an associated projectile has been discharged from a gun; to provide a safety guard which is normally held in safe or locked status by a force which 20 exerts its maximum strength when the guard is locked and diminishes in strength as the guard is released; to provide a safety guard which is held in safe or locked status by a magnetic force and released by a different 25 force; to provide a safety guard which is maintained in safe or locked status by a magnetic force and released by centrifugal force; to provide a safety guard which is formed of a plurality of members held together by a magnetic force and releasable 30 from each other under the influence of centrifugal force, to provide a safety guard formed of a plurality of magnets coacting normally with each other to maintain the 35 safe or locked status of the guard, to provide structural means assuring the correct assembly of the magnet elements of the safety guard; and to simplify and economize in the manufacture of this type of fuse 40 by reducing the number of parts to a minimum and rendering their assembly an operation of extreme ease.

I shall describe my invention in the best form known to me at present and as applied 45 to a percussion fuse, but it should be understood and apparent that it is equally applicable to other forms of fuses, such as time and combination fuses, and that it is susceptible to improvement in forms, proportions and details of construction by the 50 exercise of ordinary mechanical skill and without departing from the spirit of the invention.

Reference is had to the accompanying drawing, in which the same parts are indicated by similar letters throughout the several views.

Figure 1 is a longitudinal section of a percussion fuse showing my invention applied; an associated projectile being shown 60 in broken lines;

Figure 2, a section on the line 2—2 of Fig. 1;

Figure 3, a view similar to Figure 2 with the safety guard in released or unlocked 65 position; and

Figure 4, a detail perspective view of the primer carrier.

Referring to the drawing A is the fuse stock which is exteriorly threaded at 10 70 whereby it may be screwed into a correspondingly threaded passage in the base of the projectile indicated at B. The stock A is provided with a chamber 11, the inner end of which is reduced at 12 forming a shoulder 13 while the outer end opens through the inner end of the stock. Threaded in the chamber 11 is a primer carrier 14 having the usual flash passage 15 and primer seat 16, which latter carries a primer 17. The inner end of the primer carrier 14 is provided with an annular flange 18 forming a seat or housing for a safety guard to be hereinafter described, and having diametrically opposite recesses 19 formed therein. The 75 firing pin of my fuse is indicated generally at C and comprises a body portion 20 which seats in the reduced chamber 12, and a firing point 21 which is guided during movement of the pin in a recess 22 formed in the 80 primer carrier and leading to the primer 17. The 85

My improved safety guard which constitutes an important feature of my invention is seated in the housing formed by the flange 18 of the primer carrier and interposed normally between the body portion 20 of the firing pin and the primer 17. I form this guard of two substantially segmental magnets 23 and 24 which are assembled with the positive pole of one magnet 100 opposed to the negative pole of the other magnet whereby the magnets constituting the guard are normally held together as shown in Fig. 2 by a magnetic force and in which status the guard is interposed between the body portion of the firing pin and 105

the primer carrier to prevent movement of the pin toward the primer 17 and thus normally maintain the safe status of the fuse during handling and transportation. In 5 the form of my invention illustrated and described the magnetic force holding the elements of the guard together is adapted to be overcome by the centrifugal force due to the rotation of an associated projectile in flight 10 with the result that after the projectile is discharged the magnets 23 and 24 are moved to the position shown in Fig. 3, when the firing pin C is free to move forward and detonate the primer 17 upon the impact of 15 the associated projectile. While I have described both members 23 and 24 as magnets it will be apparent that the essence of invention in my improved safety guard would remain unaltered if only one of the members 20 constituted a permanent magnet while the other is formed of soft iron.

In order to assure the assembly of the magnets 23 and 24 with the positive pole of one opposite the negative pole of the other 25 I provide on each magnet an extension 25 which extensions are slidably engaged in respective recesses 19 and are disposed off center with respect to their related magnets. By this construction I divide each magnet 30 into long and short arms always constituting the positive pole and the long arms always constituting the negative pole or vice versa. With the magnets so arranged, it will be apparent that it would be impossible to assemble them in operative position 35 in the fuse except when the long arm of one is opposed to the short arm of the other for otherwise the long arms would overlap and prevent assembly. It will also be observed that where only one permanent magnet is employed in the guard the extensions 40 25 and recesses 19 also assure and maintain correct assembly even though said extensions are located centrally of the elements. 45 The construction just pointed out also has the advantage of locking the magnets against relative rotation with respect to a part fixed relative to the fuse stock so that the elements of the guard immediately partake of the full 50 rotation of the stock and projectile when the latter is discharged, thus assuring prompt separation of the magnets for permitting the desired action of the fuse upon impact.

55 I claim:—

1. The combination with a projectile, of a fuse including elements normally held magnetically in one relation to establish the unarmed status of the fuse and in another 60 relation by centrifugal force incident to rotation of the projectile in flight to establish the armed status of the fuse.

2. In a fuse, a stock, a firing pin, a primer, and elements carried by the stock normally

held magnetically in one relation to establish 65 the unarmed status of the fuse, and in another relation by centrifugal force to establish the armed status of the fuse.

3. In a fuse, a stock, a firing pin and primer carried by the stock, and a safety 70 guard normally holding the firing pin against movement toward the primer, said safety guard being held in restraining relation to the firing pin by magnetic force and in non-restraining relation by centrifugal 75 force.

4. In a fuse, a stock and a fuse mechanism carried by the stock including a firing pin, a primer and a safety guard comprising a plurality of members normally held together 80 by a magnetic force to provide a barrier between the firing pin and primer, and separable transversely of the stock to remove such barrier.

5. In a fuse, a stock, and a fuse mechanism 85 carried by the stock including a centrifugally released safety guard formed of a plurality of cooperating magnets.

6. In a fuse, a stock, and a fuse mechanism carried by the stock including a centrifugally released safety guard formed of 90 a plurality of members normally held in position to maintain the safe status of the mechanism by a magnetic force.

7. In a fuse, a stock, and a fuse mechanism carried by the stock including a centrifugally released safety guard normally maintaining the safe status of the fuse, said guard comprising a plurality of cooperating 100 magnets having their poles in opposed relation.

8. In a fuse, a stock, a fuse mechanism carried by the stock and including a centrifugally released safety guard formed of 105 a pair of cooperating magnets, and structural means assuring the correct assembly of said magnets.

9. In a fuse, a stock, a fuse mechanism carried by the stock and including a centrifugally released safety guard formed of 110 a pair of cooperating magnets, and structural means assuring the assembly of said magnets in a relation of opposite polarity.

10. In a fuse, a stock, a fuse mechanism carried by the stock including a centrifugally released safety guard formed of a pair of cooperating segmental magnets, and an extension on each magnet slidably engaged respectively in radial recesses formed in a part of the mechanism fixed relatively to the stock, each of said extensions being disposed off center with respect to its related magnet.

11. In a fuse, a stock, a firing pin and a primer carrier mounted within the stock, 125 said primer carrier having an annular flange on its inner end provided with diametrically opposite recesses, a centrifugally released

safety guard between the firing pin and primer carrier, said guard being formed of a pair of cooperating segmental magnets, and an extension on each magnet slidably engaged in said recesses respectively, each of said extensions being disposed off center with respect to its related magnet.

12. In a fuse, a stock, a firing pin and primer carried by the stock, a safety guard between the pin and primer comprising a pair of cooperating magnets, and means locking said magnets against relative rotation with respect to the stock and permitting

separation of the magnets under the influence of centrifugal force. ¹⁵

13. In a fuse, a stock, and a fuse mechanism carried by the stock, whose safe status is maintained by a magnetic force and its firing status established by centrifugal force.

In testimony whereof I hereunto affix my signature in the presence of two witnesses.
